UNITED STATES PATENT OFFICE.

ROBERT C. LAMBIE, OF AUSTIN, TEXAS.

CHURN-DASHER.

1,253,394.

Specification of Letters Patent. Patented Jan. 15, 1918.

Application filed September 5, 1917. Serial No. 189,621.

To all whom it may concern:

Be it known that I, ROBERT C. LAMBIE, a citizen of the United States, residing at Austin, in the county of Travis and State of Texas, have invented a new and useful Churn-Dasher, of which the following is a specification.

The present invention relates to dashers or agitators for churning and similar devices, 10 and aims to provide a novel and improved construction and assemblage of the component elements of the dasher or agitator, whereby to facilitate the agitation of the material and to aerate the same.

15 It is also the object of the invention to provide a dasher mechanism of the nature indicated which can be inexpensively manufactured, which is simple and durable in construction, which can be readily taken apart 20 for cleaning, and which will serve its office in a thoroughly efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 30 in the scope of what is claimed, without departing from the spirit of the invention.

The invention is illustrated in the accompanying drawing, wherein:—

Figure 1 is an elevation of the improved 35 dasher, portions being broken away.

Fig. 2 is a vertical section on the line 2—2 of Fig. 1.

Fig. 3 is a perspective view of the spider.

In carrying out the invention, there is provided a vertical tubular shaft 1 of suitable size having secured thereto near its lower end a ring or flange 2 provided with agitating blades 3 radiating therefrom. The ring 2 and blades 3 can be stamped from sheet metal, with the stock 4 between the blades and ring twisted so that the blades are disposed helically to give the material a vertical motion during the rotation of the shaft 1.

Extending axially through the tubular 50 shaft 1 is a shaft 5 of smaller diameter and spaced from the wall of the shaft 1 to provide a vertical air passage between said shafts, and the lower end of the shaft 5 is rounded, as at 6, to seat in a step bearing 55 for supporting the shaft 5 for rotation. Said

shaft can seat at its lower end in a step bearing provided on the bottom of the receptacle in which the dasher works, as will be readily understood. The shaft 5 has secured thereon a sleeve or hub 7, and a ring or flange 7' 60 is secured upon and surrounds the sleeve or hub 7 and is provided with agitating blades 8 radiating therefrom. The blades 8 and ring 7' can also be stamped from sheet metal, the same as the agitator above described, and 65 the stock 9 between the blades and ring is twisted so that the ends and cross sections of the blades 8 are vertical, said blades being curved to direct the material radially, while the blades 3 direct the material vertically, 70 thus obtaining a thorough agitation of the material due to the close proximity of the two sets of blades.

A spider 10 is disposed at the lower end of the tubular shaft 1, being provided with 75 a central aperture 11 through which the shaft 5 extends, and the spider is seated on the upper end of the sleeve or hub 7 of the lower agitator, and the lower end of the shaft 1 is in turn seated on the arms of the 80 spider, said arms being provided with upturned lugs 12 at their ends between which the lower end of the shaft 1 is held and centered. Thus, the shaft 1 is supported by the spider which is in turn supported by the 85 shaft 5, and said spider also holds the two shafts centered or concentric. The recesses 13 between the arms of the spider provide openings through which air can flow from the tubular shaft 1, thereby permitting air 90 to pass into the agitated material between the two agitators, to thoroughly aerate the liquid or material being worked. The two shafts are preferably rotated in opposite directions, and due to the agitation and suction created, air will be drawn downwardly 95 through the pipe 1.

A bearing or plug 15 is secured within the upper end of the tubular shaft 1 and the shaft 5 is journaled through an aperture in 100 said plug, to hold the upper ends of the shafts centered. The plug 15 has an upstanding boss 16 rotatable loosely in the bearing 15 and of non-circular contour for the engagement of means for rotating the 105 shaft 1 in one direction, and the upper protruding end of the shaft 5 has a non-circular portion for the engagement of other means to rotate the shaft 5 in the opposite direction. The shaft 1 is provided near its 110

upper end with air inlet openings 14 opening through its wall for admitting air to flow downwardly within said shaft.

The shaft 1 is preferably rotated in such a direction that the blades 3 force the material downwardly past the end of the tubular shaft 1, thus sucking the air downwardly within and from the lower end of the said tubular shaft, the material and air then being directed to the lower agitator, which, in connection with the upper agitator, thoroughly mixes the liquid and air.

Having thus described the invention, what is claimed as new is:—

- 15 1. A dasher embodying a tubular shaft, a second shaft therein, agitators carried by said shafts near their lower ends, the tubular shaft having an air passage therein, and means supported by the second mentioned shaft and supporting the lower end of the tubular shaft for the flow of air therefrom.
- 20 2. A dasher embodying a tubular shaft, a second shaft therein, agitators carried by said shafts near their lower ends, the tubular shaft having an air passage therein, and a spider supported by the second mentioned shaft and supporting the lower end of the tubular shaft for the flow of air therefrom.
- 25 3. A dasher embodying a tubular shaft, a second shaft extending therethrough, an agitator carried by the tubular shaft near its lower end, an agitator carried by the second mentioned shaft having a hub on said shaft, and a spider seated on said hub, the lower end of the tubular shaft seating

on the arms of said spider, and said arms of the spider having portions engaging the tubular shaft to hold it concentric with the second mentioned shaft.

4. A dasher embodying a tubular shaft 40 having an air inlet opening near its upper end, a bearing at the upper end of the tubular shaft, a second shaft extending through the tubular shaft and said bearing, the tubular shaft having an air passage therein, 45 an agitator carried by the tubular shaft near its lower end, an agitator carried by the second mentioned shaft below the tubular shaft, and a spider supported by the second mentioned shaft and engaging the 50 lower end of the tubular shaft to support and center it.

5. A dasher embodying a tubular shaft, a second shaft extending therethrough and spaced therefrom for the flow of air through 55 the tubular shaft, agitators carried by the shafts near the lower ends thereof, the lower end of the tubular shaft being open between the agitators for the flow of air therebetween, and the agitators being arranged to 60 impel the liquid away from said open end of the tubular shaft to draw air downwardly therethrough.

In testimony that I claim the foregoing as my own, I have hereto affixed my signature in the presence of two witnesses.

ROBERT C. LAMBIE.
